CLAIM

The ornamental design for a paintball gun, as shown and described.

DESCRIPTION

FIG. 1 is a perspective view of a paintball gun of the invention.

FIG. 2 is a left side view of the paintball gun of FIG. 1, the right side view being a mirror image thereof;

FIG. 3 is a top view of the paintball gun of FIG. 1.

FIG. 4 is a bottom view of the paintball gun of FIG. 1.

FIG. 5 is a front view of the paintball gun of FIG. 1; and, FIG. 6 is a rear view of the paintball gun of FIG. 1.

The broken lines in the figures are for environmental purpose only and form no part of the claimed design.

1 Claim, 6 Drawing Sheets
